UNITED STATES PATENT OFFICE

2,327,809

MOTOR CONTROL SYSTEM

Charles MacDonald, Evanston, Ill., Jacob W. McNairy, Bridgeport, Conn., and John F. Tritte, Erie, Pa., assignors to General Electric Company, a corporation of New York

Application August 22, 1941, Serial No. 407,872

24 Claims. (Cl. 172—179)

This invention relates to motor control systems, more particularly to systems of control for electric motor driven trolley busses or coaches utilizing a series motor, and has for its object a simple and reliable acceleration and dynamic braking control system providing for a predetermined limiting rate of acceleration and dynamic braking and preadjustment of the dynamic braking resistance in accordance with speed when power is taken off the driving motor thereby to provide a quick dynamic braking response.

Our invention has a special application to trolley bus control systems of the type described and claimed in United States Patent No. 2,198,481, issued on April 23, 1940, to Jacob W. McNairy and Charles MacDonald, wherein the controls for acceleration and dynamic braking are operated by separate pedals, thereby to simulate the operation of the conventional mechanically driven automobile.

A further object of our invention is a control system wherein the return of the acceleration controller to its off position initiates the operation of control means to adjust the starting resistance for the motor in accordance with the speed of the vehicle so that the resistance is pre-selected at a suitable value to give effective dynamic braking quickly upon depression of the braking pedal.

Another object of the invention is means for establishing dynamic braking immediately by depression of the brake pedal without the prior application of power to the motor, for example, in the event that the vehicle starts rolling from standstill down a steep grade.

Still another object of the invention is the utilization for dynamic braking of the same resistor short-circuiting contactors that are used during acceleration with the addition of one or more steps as required by control of the field of the motor.

In carrying out our invention in one form, we provide contactors for controlling the resistance during both acceleration and deceleration together with a relay which is responsive to the current in the motor circuit for automatically controlling these contactors and also for controlling the field of the motor during dynamic braking.

We also provide a dynamic braking relay which is picked up and locked in by operation of the acceleration controller to start the motor, which relay remains picked up when the controller is returned to its off position and thereby effects the preadjustment of the resistance for dynamic

braking during coasting operation of the vehicle. Another feature is switching means incorporated in the braking controller for picking up this dynamic braking control relay immediately upon depression of the braking pedal thereby to start dynamic braking without first applying energy to the motor by operation of the acceleration controller.

For a more complete understanding of our invention, reference should be had to the accompanying drawings, Fig. 1 of which is a diagrammatic representation of a system of control for a trolley bus embodying our invention; Fig. 2 is a layout diagram of the acceleration controller; Fig. 3 is a layout diagram of the braking controller; Fig. 5 is a sequence chart of the principal contactors and relays shown in Fig. 1; Fig. 6 is a layout diagram of the reversing controller; while Fig. 4 is a diagrammatic representation of the operating mechanism for the braking controller.

Referring to the drawings, we have shown our invention in one form as applied to a system of control for a trolley bus or coach driven by a series direct current motor provided with an armature 10 and a series field winding 11. The motor may be connected for operation to the direct current supply mains 12 and 13, which may be energized from suitable trolleys bearing on overhead trolley wires, an accelerating resistance 14 being provided which is cut out in sections by the short-circuiting switches or contactors R1 to R8 inclusive.

The acceleration of the motor 10 is effected by means of a rotatable controller 22 (Fig. 2) which may be moved forward step by step or which may be turned immediately to a full speed position. In the latter case, the acceleration of the motor is controlled by means of a relay ABR having a current coil 24 connected in series with the armature 10, and a current responsive coil 25 utilized during dynamic braking.

The connections of the motor for dynamic braking are controlled by a braking controller 26 (Fig. 3) which when turned to a braking position 45 causes the short-circuiting of the braking resistance to be controlled by the coil 25 of the ABR relay to maintain a predetermined braking current and torque.

As shown, the control circuits are supplied from 50 separate supply mains 27 and 28 which are connected to a suitable supply source, for example, to a 36-volt storage battery (not shown). The mains 12 and 13 supplying the motor may, for example, be supplied from a 600-volt trolley circuit. One advantage of this separate storage

battery source of supply for the control circuits is that dynamic braking of the motor can be obtained even in the event of a failure of the supply source to the high voltage mains 12 and 13.

Acceleration

It will be assumed that the acceleration controller 22, which is manually operated by a handle or preferably by a foot pedal (not shown), is turned from the off or coast position shown in Fig. 2 immediately to its sixth and full speed running position so that all of its acceleration controlling switches are closed. The first acceleration controller switch A30 to be closed energizes the LB (line breaker) coil 31 which closes the LB switch in the motor circuit and also the LB interlock switch 33. This circuit for the coil 31 is from the supply main 12 through the switch A30, coil 31, B (braking) interlock switch 34, and OLR (overload relay) switch 35 to the supply main 13.

The LB interlock switch 33 feeds current during acceleration to the operating coils of the contactor or switches R1 to R8, F1 and F2. It first closes a circuit through the R1 switch operating coil 36, this circuit leading from the supply main 27 through the reversing switch 37, the conductor 38, switch 33, conductor 38a, R1 interlock switch 39, the coil 36, R1 interlock switch 40, R7 interlock switch 41, the lower ABR contact 42 to the supply main 28. Thereupon the coil 36 picks up its armature, closing the R1 switch for completion of the motor circuit, opening its interlock switch 40, and closing its interlock switch 44 before the opening of switch 40 to establish a holding circuit for the coil 36 independent of the contact 42 on the relay ABR.

At this time, the motor circuit is closed by the closing of the LB switch and the R1 switch with all of the resistance 14 in circuit with the motor.

It should be noted that the R1 interlock switches 40 and 44 are of a walking beam floating contact bar type, these two switches having a single straight movable contact arm to which the reference numerals 40 and 44 are applied. This arm is pivotally mounted centrally on a pivot 45 carried by the operating armature of the R1 coil 36 or a member actuated by the armature. As shown, with the coil 36 deenergized, the left-hand end of this contact arm constituting the movable arm of the switch 40 is biased downward into engagement with the left-hand contact by means of a spring 46, while the other end of the arm is disengaged from the right-hand contact. When the coil 36 is energized, the pivot 45 is lifted by the armature of the coil 36 thereby first to raise the right-hand end of the contact arm constituting the movable arm of switch 44 into engagement with the right-hand stationary contact which is above the arm as seen in the drawings. Further upward movement of the pivot 45 lifts the left-hand end of the contact arm against the force applied by the spring 46 to disengage the left-hand contact which is below the arm. The spring now holds the right-hand end of the contact arm against the right-hand contact. This constitutes a simple and reliable switching means for first closing a holding circuit for the coil 36 and thereafter opening the pick-up circuit of the coil. During this movement it will be observed that the contact arm first pivots on the left-hand contact until the right-hand contact is engaged, and then pivots on the right-hand contact to disengage the left-hand contact.

Since it was assumed that the accelerating controller 22 was moved to the full on position, the accelerating controller contacts A47 to A51 are all closed. Ordinarily, when the motor circuit is first closed, the current in the ABR coil 24 is great enough to pick up its armature and open the switch 42, whereby closing of additional resistance short-circuiting switches is momentarily prevented. When the motor current drops upon acceleration of the motor, the switch 42 closes at the drop out current value for which the relay is set and closes the circuit for the R2 coil 52. This circuit leads from the R7 switch 39 through F1 interlock switch 53, which is now closed, the A47 switch, coil 52, R2 switch 54, R1 interlock switch 55, which is now closed, R7 interlock switch 41 and the switch 42 to the supply main 28.

Upon its energization, the R2 coil 52 first closes an interlock holding switch 56 and then opens its switch 54. It will be understood that these switches 54 and 56, and others which are shown in the drawings in the same manner as the switches 40 and 44, are of the walking beam type and operate in the manner described in connection with the latter switches.

The coil 52 also closes the R2 switch to short-circuit the first section of the resistance 14 and closes an interlock switch 57 to provide for the energization of the R3 coil 58 under the control of the ABR relay.

As the motor accelerates and the ABR switch 42 recloses, the R3 coil 58 is energized, the circuit leading from the F1 switch 53 through the A48 switch, the coil 58, its interlock switch 59, the switch 57 which is closed and thence through the R1 switch 41 and the switch 42 to the main 28. The coil 58 then closes the next resistance short-circuiting switch R3 and closes its interlock switch 60 for the next coil R4 61, the coil 68 establishing a holding circuit for itself, as will be understood from the description of the coils 36 and 52.

Assuming that the acceleration controller 27 remains in its full on or sixth position, the acceleration continues automatically under the control of the ABR relay, and the coils R4 61, R5 62, R6 63 and R7 64 are successively energized in the order mentioned in a manner which will be understood with reference to the preceding description.

It will be noted that the coils for the R1 to R6 switches are all energized through the R7 39 switch, which is normally closed. Therefore, when the R7 switch closes, opening the R7 39 switch, these coils are all deenergized and the R1 to R6 switches drop open.

Also, it will be noted that the R1 coil 36 is energized independently of the acceleration controller switches. The remaining coils, however, are energized through various acceleration controller switches and, consequently, if the acceleration controller is turned only part way to its full running position, the acceleration stops at the point determined by the controller position. Thus, if the acceleration controller is moved to its first position only, the R1 36 coil only is energized. Movement of the acceleration controller to the second position, closing its A47 switch, results in energization of the R2 coil 52, whose circuit is through the A47 switch. Movement of the acceleration controller to the third position closes its switch A48 which is in circuit with the R3 58 and R4 61 coils and, consequently, it makes possible the energization of these coils. The A49

switch closed in the fourth position of the acceleration controller sets up a circuit for the R5 coil 62 and the R8 coil 63. In the fifth position of the acceleration controller, the A50 switch is closed for energization through the conductor 50a of the R1 64 and R8 65 coils. Finally, in the sixth position, the A51 switch is closed and sets up a control circuit for the F1 74 coil and the F2 75 coil.

It will also be noted that the coils 61 to 65 inclusive are initially energized through the conductor 66, leading directly to the ABR switch 42 without going through the R7 41 switch.

As previously noted, when the R7 switch closes and thereby short-circuits all of the resistance except the left-hand section 14a, the R7 interlock switch 39 opens the circuits of the coils for the R1 to R6 switches and these switches therefore open for subsequent sequencing operation as indicated clearly on the sequence chart Fig. 5, whereby various control combinations of the sections of the resistance 14 are made thereby gradually to reduce the resistance in the motor circuit for further acceleration. This is described below.

When the R8 switch closes, connecting the remaining sections of the resistance 14 in series with each other and in parallel with the left-hand section, its interlock switch 67 closes and establishes again a pick-up circuit for the coils of the switches R1 to R6, the R7 39 switch being open. Also, a second R8 switch 68 is closed, whereby the R4 61 coil is next energized for closure of the R4 switch under the control of the ABR relay. The R4 switch short-circuits the three left-hand sections of the resistance 14. The coils of the R1, R2 and R3 switches are not energized at this time and these switches are therefore not closed because of the fact that the R7 switch 41 is now open. The coils of the R5 and R6 switches, however, are energized in succession to cut out additional sections of the resistance 14.

With the R6, R7 and R8 switches closed and the R1 switch open, the two left-hand sections of the resistance 14 only are connected in parallel with each other in the motor circuit.

In closing the R6 switch closes its switch 69 in the circuit of the R1 coil 36, whereby the R1 switch is next closed under the control of the ABR relay as before. With the R1 and R8 switches now closed, the entire resistance 14 is short-circuited. The circuit for the R1 coil may be traced from the supply main 27 through the switch 31, wire 38, switch 33, R8 switch 67, R1 coil 36, R1 switch 40, conductor 70, R6 switch 69, R8 switch 68, conductor 66 and ABR switch 42 to the supply main 28.

Two additional points of acceleration are obtained by successively closing the F1 switch and the F2 switch to shunt and thereby weaken the motor field. The F1 switch in closing connects a resistance 72 and a reactance 73 in series with each other across the field winding 11, while the F2 switch in closing short-circuits the resistance 72. The coils 74 and 75 of these field shunting switches are controlled successively by the ABR relay after the closing of the R8 interlock switch 76 and the closing of the R1 switch 78. The circuit for the coil 74 is traced from the supply main 27 through switch 37, wire 38, switch 33, acceleration switch A50 which is now closed, acceleration switch A51 which is closed, R8 switch 76, coil 74, F1 switch 77, R1 switch 78 which is now closed, LB switch 79 which is

closed to the conductor 66 and through the ABR switch 42 to the main 28.

The closing of the F1 interlock switch 80 sets up a circuit for the F2 coil 75, this circuit leading through the A51 switch as previously traced and then through the coil 75, the F2 switch 31, switch 80, LB switch 82 to the conductor 66 and through the ABR switch 42 to the main 28.

The motor is now running at full speed with 10 the resistance 14 short-circuited and the field 11 weakened by field shunting, the F1 and F2 switches being both closed.

It is contemplated that the ABR current coil 24 will regulate its switch 42 so as to maintain the motor current below a predetermined maximum value during starting. Since holding circuits for the various contactors when they close are set up independently of the switch 42, this switch has no control over the motor during running conditions after the acceleration period is over. In the event of an overload under running conditions and also during acceleration, the OLR (overload relay) coil 83 opens its switch 35 and thereby deenergizes the LB coil 31, whereupon the LB switch opens to disconnect the motor from the supply circuit. Also, the OLR switch 84 closes to close a circuit for the OLR holding coil 35. This switch 84 is arranged to close before the switch 35 opens. It connects the coil 35 momentarily in parallel circuit with the LB coil 31, and the coil 85 holds the switch 35 open and the LB coil 31 deenergized after the motor circuit is opened by the opening of the LB switch. In order to reenergize the motor, it is necessary to return the acceleration controller 22 to its off position so as to open its switch A38 and deenergize the coil 85 for reclosure of the OLR switch 35.

Coasting

Dynamic braking circuits are set up upon the return of the acceleration controller 22 to its off or coasting position for automatic adjustment of the resistance 14 in the braking circuit 45 in accordance with the speed of the motor, but dynamic braking becomes effective only when the braking controller 26 is moved to a braking position. With the controller 22 operated by means of a pedal (not shown), it is biased 50 by a suitable spring (not shown) to this off or coast position and returns to that position when the pedal is released. In that position, it will be observed from Fig. 2 that the switches A47, A48, A49, and A50 after being opened are again 55 closed when the controller 22 reaches its full off or coasting position. The opening of the acceleration controller switch A30 deenergizes the coil 31 whereby the LB switch opens. Also, the LB switch 33 opens and deenergizes the operating coils of the contactor or switches R1 to R8 and F1 and F2 whereupon these contactors drop open.

During acceleration the BR (braking relay) coil 87 is energized in preparation for braking 65 through the LB interlock switch 88 which is then closed. This circuit is from main 27 through switch 37, switch 38, BR coil 87, OLR switch 89 to the main 28. The BR interlock switch 90 then closes and establishes a holding circuit for the coil 87 leading from wire 38, wire 82, through the B switch 91 which is closed, BR switch 90, coil 87 and switch 89 to the main 28. Therefore, the BR coil 87 remains energized after the acceleration switch 22 is returned to its off or coast position.

The BR interlock switch 93 is closed partially to close circuits to the supply main 28 for the B coil 94 and the FF (field flashing) coil 95 in preparation for dynamic braking when the line breaker LB drops out. Also, the BR switch 93 partially closes a circuit for the AR coil 96 whereupon this relay picks up when the A98 switch is closed. The circuit for the AR coil 96 is from main 27 through switches 31, 97, A98, R4 switch 99, B switch 100, coil 96, BR switch 93 and OLR switch 89 to the main 28. A holding circuit in parallel with the B switch 100 is established by the closing of the AR switch 101.

When the line breaker LB opens, its interlock switch 97 closes a circuit for the B coil 94 and the FF coil 95 in parallel with each other. This circuit leads through the acceleration switch A98 which is closed, the coils 94 and 95 in parallel with each other, BR switch 93 which is closed and OLR switch 89 to the main 28. A holding circuit in parallel with the B switch 100 is established by the closing of the AR switch 101.

A circuit to maintain the BR coil 87 energized is established by the B interlock switch 103 before the B switch 91 opens, this circuit having an R1 holding switch 104 and an R8 holding switch 105 connected in it in parallel with each other and leading through the FF switch 106. It may be traced from the conductor 38 through conductor 92, switch 103, through either one or both of the switches 104 and 105 and then through the FF switch 106, the BR coil 87 and OLR switch 89 to the main 28. This provides for the pickup of either the R1 switch 104 or the R8 switch 105 without deenergizing the BR coil 87. When both of these switches are picked up, however, at the same time the BR coil 87 is deenergized. It should be noted that the B switches 91 and 103 constitute a walking beam switch as hereinbefore described in connection with the R1 switches 40 and 44. Also, the B switch 103 when closed provides for a supply of energy from the conductor 92 to the conductor 38a for the operation of the R1 switch, and the resistance controller contactor switches R2 to R8 under the control of the ABR relay switch 42.

During coasting the R1 switch is first closed, the circuit for the R1 coil 36 now being through the conductor 92, B switch 103 which is closed, R7 switch 39 which is closed, the coil 36, the R1 switch 40, R7 switch 41 and ABR switch 42 to the main 28. The closure of the R1 switch completes the dynamic braking circuit from the right-hand side of the armature 10 through the resistance 14, the R1 switch, conductor 108, permanent braking resistance 109, B switch 100a, field winding 11 which is then reversed, OLR coils 83 and 110 and the B switch 99a back to the left-hand side of the armature 10. At this time, current is supplied for field forcing from the main 12 through the FF switch 102, resistance 111, OLR coils 110 and 83, field winding 11, B switch 100a, resistance 109, conductor 108, and the ABR coil 24 to the main 13. This field forcing circuit, it will be observed, is established by the closing of the switches FF102 and B100a independently of the R1 switch, which completes the dynamic braking circuit.

The motor now builds up as a generator with full field excitation and the ABR coil 25 now controls the successive closing of the resistance switches R2 to R8 in response to the voltage drop across the resistance 109 and therefore in response to the current in the braking circuit and the speed of the motor. It should be noted that

the switches B111 and A86 are now closed and connect the coil 25 directly across the resistance 109 for the most sensitive response of the coil, whereby the braking control coil 25 operates to maintain a predetermined low coasting current in the braking circuit, such as 25 amperes, which is so low that no appreciable dynamic braking effort is produced.

The function of the auxiliary relay AR is to control the field shunting switch F1 so as to provide a weakened motor field for the coasting follow-up, and also to provide the required number of control steps for braking without resorting to additional resistor steps and contactors over those required for acceleration.

The B switch 112 is now closed during coasting and the switch B113 is also closed during coasting and these two switches establish a circuit for the AR coil 96 in parallel with the R4 switch 99 and the AR switch 101. Consequently, during coasting the R4 switch 99 can open without opening the circuit of the AR coil 96 and the AR relay remains in its picked up position throughout coasting. If the braking controller is turned to a braking position, whereby the B113 switch is opened, while the vehicle is still operating at a high speed, the AR relay is deenergized when the R4 switch closes. The AR relay in dropping out opens the F1 switch to reestablish full field excitation and also causes the R2 and R8 switches to drop out. The switches R2 and R8 are now closed in sequence with full field excitation under the control of the ABR relay. This operation will be described more in detail under dynamic braking operation.

If coasting is initiated by turning the acceleration controller to its off position while the vehicle is operating at a speed above 30 miles per hour, the low coasting or spotting current is established very quickly and the ABR coil 25 picks up its switches, the ABR switch 114 closing a circuit for the F1 coil 74. This circuit leads from the conductor 92 through the B103 switch, conductors 38a and 50a, A50 switch which is now closed, AR switch 115, coil 74, F1 switch 11, AR switch 116, conductor 117 and the ABR switch 114 to main 28. The F1 switch now closes for field shunting through the resistance 72 and inductance 73 for reduced field excitation. A holding circuit for the F1 coil 74 is established by the closing of the F1 switch 118 through the conductor 119 directly to the main 28.

If coasting is initiated at a low speed, the ABR relay may not pick up and, in that case, the field 55 F1 remains fully excited. Also, of course, the ABR relay may not pick up until after one or more of the switches R2 to R8 have closed. In any case, during coasting the switches R2 to R8 are closed in sequence as previously described, 60 but when the ABR relay picks up, these switches are thereafter controlled with a weak field because of shunting of the motor field.

Because of the fact that the BR coil 122 also is connected directly across the resistance 109 during coasting, the B111 switch being closed, and has a very sensitive response to braking current, the coil 122 holds the BR relay in its picked-up position during coasting down to a low speed such as 5 miles an hour when the BR relay opens and deenergizes all of the control circuits.

Dynamic braking

When the braking controller 26 is turned to a 75 braking position thereby to establish effective

dynamic braking, the acceleration controller 22 being in its off position, the B111 switch is opened, whereby a resistance 123 is inserted in series with the ABR coil 25 and the BR coil 122. These two coils are now connected in parallel with each other through the A86 switch and in series with the resistance 123 across the resistance 109. This decreases the braking current response of the coil 25, i. e., raises its current setting. Also, the resistance 123 reduces the current in the coil 122, which coil is not effective in the control at this time because the BR87 coil is energized through the B132 switch. The ABR relay then operates to maintain a predetermined greater current in the braking circuit which gives effective dynamic braking.

In the event that the braking controller is turned to a braking position when the vehicle is moving at a speed of more than 30 miles per hour, the ABR relay picks up immediately and energizes the F1 coil 74 as previously described. This closes the F1 switch and establishes field shunting and weak field excitation. The R2 and R3 switches now close under the control of the ABR relay as the vehicle speed decreases, thereby to maintain the predetermined braking current.

When the R4 switch is picked up, however, it opens its switch 99. But movement of the braking controller to a braking position has opened the switch B113 and, consequently, the AR coil 96 is deenergized by the opening of the R4 switch 99. The AR switches 115 and 116 in circuit with the F1 coil 74 now open and open the F1 switch to reestablish full field excitation. Also, the AR switch 126 opens and thereby opens the circuit of the R2 and R3 coils, whereby these switches open.

It will be noted that during braking the coils of the R2 and R6 switches inclusive are fed through either the normally closed F1 switch 53 or through the normally open AR switch 126. Therefore, when either of these switches is closed, the resistance switches can be picked up in normal sequence. With the F1 switch 53 now closed, the switches R2 to R6 close in sequence with full field excitation.

It is believed that the sequencing of these switches under the control of the ABR relay will be understood from the description in connection with the acceleration. In view of the fact that the AR relay has been dropped out, its switches 115 and 116 are open and therefore the F1 field shunting switch cannot be closed. The F2 field shunting switch cannot be closed during dynamic braking because of the fact that the A51 switch is open at that time.

The F1 coil 74 is provided with suitable timing means to provide a time interval in the dropout of its armature or core after the circuit of the coil has been opened, such as a dash pot 27 or a short-circuited copper sleeve (not shown) between the coil and the core. This time interval is sufficient to provide for opening of the switches R2, R3 and R4 before the F1 switch 53 closes during braking at high speeds.

As the deceleration of the vehicle proceeds, the R1 and R3 switches or contactors are both closed when the resistance 14 has been cut out of the braking circuit and, consequently, the R1 switch 104 and the R3 switch 105 are both open at that time. Also, at this time the contactors R2 to R7 are all closed as indicated in the last braking step, No. 15, on the sequence chart, Fig. 5. The opening of the switches R1-104 and

R8-105 transfers the control of the circuit of the BR coil 87 to the braking controller switch B132 which is closed as long as the braking controller 26 is held in a braking position. Therefore, as long as the braking controller 26 is held in a braking position, the BR coil 87 remains energized and the dynamic braking connections are maintained. If the braking controller is held in its braking position until the vehicle 10 comes to rest, or even longer, the braking connections are maintained.

This feature of positively maintaining the dynamic braking connections by means of the switch B132 is important when the vehicle is operated in very hilly regions or where the grades are severe enough to warrant this extra protection from the standpoint of safety. Thus if the vehicle starts to roll down a grade, dynamic braking can be established immediately by depressing the braking controller pedal 128, without the necessity of first applying power to the vehicle to set up the braking circuits.

If the braking controller 26 is released and allowed to move to its off position by means of its 25 biasing spring when the vehicle is moving at a substantial speed, the B132 switch being opened, the BR coil 87 is deenergized if or when the switches 104 and 105 both are opened. The BR relay is then held in its picked-up position by the 30 BR coil 122, the B111 switch being closed for maximum energization of the coil 122, until the vehicle speed is reduced to some low speed such as 5 miles an hour at which the energization of the BR coil 122 will have decreased to a low value 35 such that the BR relay drops open and its switch 93 opens to open the circuits of the B coil 94 and the FF coil 95 thereby to open the dynamic braking circuit. It will be observed that the B interlock switch 103 now opens and deenergizes the 40 operating coils of all of the switches or contactors R1 to R7 inclusive.

During dynamic braking, the current setting of the ABR relay can be raised to call for greater dynamic braking by further depression of the 45 braking controller pedal 128 (Fig. 4) whereby a spring 129 connected between the pedal and the ABR relay is stretched, thereby to apply a force tending to hold the relay in its deenergized position.

50 When the braking controller 26 is operated to a braking position, its switches B130, B131 and B132 are closed and its switch B133 is opened.

The B130 switch in closing sets up the circuit for the OLR holding coil 85 so that the coil 85 55 can be energized independently of the switch A30 which is open. The opening of the B133 switch prevents the connection of the coil 85 in parallel with the coil 31, which coil is deenergized during braking. If the OLR relay picks up in response 60 to an excessive current, however, its switch 84 closes a circuit for the coil 85 between the mains 12 and 13, and this coil then holds the OLR relay picked up. The OLR switch 89, then being open, opens the circuit for the B coil 94, the AR coil 96 and the BR coil 87, thereby to interrupt the dynamic braking connections. To again apply dynamic braking, the braking controller must be returned to its off position, thereby to open the switch B130 and deenergize the OLR coil 85.

70 The OLR braking coil 110 applies a force which is in the same direction as the force applied by the coil 83 to their common armature. In other words, these two coils are additive in their effects and consequently the OLR relay is picked up 75 by a lower current during braking than during

motoring operation. This is because the electric braking rate is normally less than the accelerating rate on account of reverse torque limitations of the rear axle drive, i. e., 2 mphps. as compared with 3 to 4 mphps.

We have also provided a manually operated double throw switch 134 which is normally maintained closed as by a spring as shown in the circuit of the A51 switch. When this switch is moved to its other position, it energizes an auxiliary ABR coil 135, and opens the circuit leading from the A51 switch. This coil 135 opposes the coil 28. It serves to raise the current setting of the ABR relay to provide sufficient acceleration when climbing steep grades. The opening of the circuit leading from the A51 switch prevents progression of the control to shunt the field and thereby prevents excessive current with weakened field under extreme conditions.

A reversing switch 136 (Fig. 6) which is manually operated is provided for the motor field winding 11. This switch, which is of the drum type, is shown in the forward position. In addition to the usual central off position and a forward and a reverse position on opposite sides of the off position, two emergency positions are provided which are reached respectively by continued movement of the reversing switch in the reverse or the forward direction.

In the emergency position of the reversing switch, a long segment 137 electrically connects together the points 138, 139 and 140, and a shorter segment 141 electrically connects together the points 142 and 143, whereby the motor field 11 is connected for forward rotation of the motor, its connection thereby being reversed. Also, the connection of the point 138 with the point 139 closes a low resistance dynamic braking circuit through the conductor 144 and containing the left-hand section 14a only of the resistance. This circuit can be traced from the point 139 through the reversing controller to the point 138, the conductor 144, the resistance section 14a, the motor armature 10, the B switch 101a which is closed and through the reversing switch and the field winding 11 back to the point 139. When the reversing switch is moved to the other emergency braking position, the three segments 145, 146, and 147 establish the same dynamic braking circuit, but with the motor field reversed with respect to the first mentioned emergency position. The reversing switch 37 is maintained closed by an operating cam 148 on the reversing switch when the switch is in its reverse, off, and forward positions. When the switch is thrown to either of its emergency positions, however, the switch 37 opens and deenergizes all of the low voltage control circuits from the supply main 27.

This emergency braking with the reversing switch is for use in the event that all other braking systems fail. If the vehicle is moving forward, the emergency switch is rotated by means of its handle (not shown) beyond the forward position to the right hand emergency position shown in Fig. 6, whereby the field is reversed with respect to the forward position and the braking circuit established by the segments 145, 146, and 147. In the same way, if the reversing switch is in the reverse position for reverse movement of the vehicle, the emergency dynamic braking is established by continuing the rotation of the switch to bring the segments 137 and 141 into position to establish this dynamic braking circuit with the motor field winding reversed with respect to the reverse position.

While we have shown a particular embodiment of our invention, it will be understood, of course, that we do not wish to be limited thereto, since many modifications may be made and we, therefore, contemplate by the appended claims to cover any such modifications as fall within the true spirit and scope of our invention.

What we claim as new and desire to secure by Letters Patent of the United States is:

1. The combination, in a propulsion system for a vehicle, of a traction motor, an acceleration controller movable from a predetermined position to a running position to establish a supply circuit for said motor, a braking relay for controlling dynamic braking of said motor having a coil energized to pick up said relay in response to movement of said acceleration controller to a running position thereby partially to complete dynamic braking connections for said motor, means for holding said relay in its energized position, and means operated by said acceleration controller for completing said dynamic braking connections when said acceleration controller is returned to said predetermined position.
2. The combination in a propulsion system for a vehicle, of a traction motor, a braking resistance for said motor, an acceleration controller movable from a predetermined position to a running position to establish a supply circuit for said motor, a braking relay for controlling dynamic braking having a coil energized to pick up said relay in response to movement of said acceleration controller to a running position thereby partially to complete dynamic braking connections for said motor, means operated by said coil for establishing a holding circuit for said coil so that said coil remains energized when said acceleration controller is returned to said predetermined position, and means operated by said acceleration controller for completing said dynamic braking connections when said acceleration controller is returned to said predetermined position whereby a dynamic braking circuit for said motor is established including said resistance.
3. The combination in a propulsion system for a vehicle, of a traction motor, a braking resistance for said motor, an acceleration controller movable from a predetermined position to a running position to establish a supply circuit for said motor, a braking relay for controlling dynamic braking having a coil energized to pick up said relay in response to movement of said acceleration controller to a running position thereby partially to complete dynamic braking connections for said motor, means operated by said coil for establishing a holding circuit for said coil so that said coil remains energized when said acceleration controller is returned to said predetermined position, means operated by said acceleration controller for completing said dynamic braking connections when said acceleration controller is returned to said predetermined position whereby a dynamic braking circuit for said motor is established including said resistance, a braking coil responsive to the current in said braking circuit for controlling said braking resistance to maintain a predetermined low coasting current in said braking circuit, and a braking controller movable to decrease the current response of said braking coil thereby to initiate dynamic braking.
4. The combination, with a traction motor provided with a field winding, means for controlling

the acceleration of said motor, a manually operated reversing switch for said field winding provided with forward and reverse running positions and with a braking position beyond one of said running positions, and switching means in said reversing switch in said braking position for reversing said field winding with respect to said adjacent running position and for establishing a dynamic braking circuit for said motor.

5. The combination, with a traction motor provided with a field winding, of an acceleration controller movable to establish a supply circuit for said motor for acceleration of said motor, means responsive to the current in said motor for controlling said resistance to accelerate said motor, a manually operated reversing switch for said motor provided with forward and reverse running positions and with two emergency braking positions respectively beyond the said forward and reverse positions, and switching means in said reversing switch in each of said emergency positions for establishing a low resistance dynamic braking circuit for said motor.

6. The combination, with a traction motor provided with a field winding, of an acceleration and braking resistance for said motor, means for establishing a supply circuit for said motor for acceleration of said motor and a dynamic braking circuit for said motor, means responsive to the current in said motor for controlling said resistance during acceleration and dynamic braking of said motor, a manually operated reversing switch for said field winding provided with forward and reverse operating positions and with two emergency dynamic braking positions respectively beyond the said forward and reverse positions, and switching means in said reversing switch in each of said emergency positions for reversing said field winding with respect to said adjacent forward or reverse position respectively and for establishing a dynamic braking circuit for said motor.

7. The combination with a traction motor provided with a field winding, of an acceleration and braking resistance for said motor, switching means for controlling said resistance to control the acceleration and braking of said motor, a running operating coil responsive to the current in the circuit of said motor and operating to control said switching means so as to maintain a predetermined current in said motor during acceleration, a manually operated acceleration controller movable from a predetermined position to a running position to establish a supply circuit for said motor through said resistance, means operated by said acceleration controller upon the return of said controller to said predetermined position to connect said motor in a dynamic braking circuit with said resistance but excluding said running operating coil, a braking operating coil having an armature responsive to the current in said braking circuit thereby to control said switching means to maintain a predetermined low coasting current in said braking circuit which does not give any appreciable dynamic braking effort, a braking controller, an operating pedal connected to move said braking controller to a dynamic braking position, means responsive to movement of said braking controller to said braking operating coil thereby to initiate dynamic braking, whereupon said braking operating coil controls said switching means to maintain a predetermined dynamic braking current, a resilient connection between said pedal and said armature of said braking operating coil

for applying an increasing biasing force to said armature upon further movement of said pedal thereby to decrease the current response of said braking operating coil, means operated by said braking operating coil for partially disabling said field winding, and means operated by movement of said acceleration controller to a running position for disabling said last named means.

- 10 8. The combination with a traction motor, of an acceleration and braking resistance for said motor, a plurality of electromagnetically operated switches for short-circuiting said resistance to control the acceleration and braking of said motor, a control relay for controlling said switches, a running operating coil for said relay responsive to the current in the circuit of said motor and operating said relay to control said switches so as to maintain a predetermined current in said motor during acceleration, a manually operated acceleration controller movable from a predetermined position through a plurality of running positions to establish a supply circuit for said motor through said resistance and for limiting the operation of said switches in accordance with the running position of said acceleration controller, thereby to limit the speed to which said motor accelerates, switching means operated by said acceleration controller upon the return of said controller to said predetermined position to connect said motor in a dynamic braking circuit with said resistance but excluding said running operating coil, a braking operating coil for said control relay connected so as to be responsive to the current in said braking circuit and thereby control said switches to maintain a predetermined low coasting current in said braking circuit which does not give any appreciable dynamic braking effort, a braking controller, an operating pedal connected to said braking controller so as to move said braking controller when said pedal is depressed to a dynamic braking position, means responsive to movement of said braking controller to said braking position for decreasing the current response of said braking operating coil thereby to initiate dynamic braking, whereupon said braking operating coil controls said switching means to maintain a predetermined dynamic braking current, and a resilient connection between said braking controller and said relay for applying an increasing biasing force to said relay upon further depression of said pedal thereby to decrease the current response of said braking coil and increase the dynamic braking current maintained by said relay.
- 15 9. The combination with a traction motor, of a braking resistance for said motor, said motor being provided with a field winding, switching means for controlling said resistance, a braking control coil responsive to the current in said motor during dynamic braking of said motor for controlling said resistance switching means, means for disabling said field winding controlled by said braking coil, a normally open auxiliary relay switch for controlling said field disabling means provided with an operating coil, connections for energizing the operating coil of said auxiliary relay, whereby said auxiliary relay switch is closed to set up a circuit for the operation by said braking coil of said field disabling means to disable said field winding in response to a predetermined dynamic braking current, a braking controller movable from a predetermined position to another position to initiate dynamic

braking for said motor, means operated by said resistance switching means after exclusion of part of said resistance from the dynamic braking circuit for deenergizing said auxiliary relay operating coil thereby to establish full excitation of said field winding, means operated by said auxiliary relay when deenergized for controlling said resistance switching means to insert said resistance in said dynamic braking circuit when said auxiliary relay is deenergized, and a normally closed switch which is closed by the operation of said field disabling means to establish full excitation of said field winding thereby to set up a circuit for operation of said resistance switching means under the control of said braking coil.

10. The combination with a traction motor, a braking resistance for said motor, said motor being provided with a field winding, switching means for controlling said resistance, a braking control coil responsive to the current in said motor during dynamic braking of said motor for controlling said resistance switching means, a normally open switch movable to closed position to shunt said field winding provided with an operating coil, a normally open switch in circuit with the operating coil of said field winding switch operated by said braking coil, a normally open auxiliary relay switch provided with an operating coil, connections for energizing the operating coil of said auxiliary relay whereby said auxiliary relay switch is closed partially to set up a circuit for the operating coil of said field shunting switch for closure of said field shunting switch by said braking coil in response to a predetermined dynamic braking current, a braking controller movable from a predetermined position to another position to initiate dynamic braking for said motor, means operated by said resistance switching means to deenergize said auxiliary relay operating coil thereby to open the operating coil circuit of said field shunting switch and establish full excitation of said field winding, means operated by said auxiliary relay when deenergized for controlling said resistance switching means to insert said resistance in said dynamic braking circuit when said auxiliary relay is deenergized, and a normally closed switch which is closed when said field shunting switch opens thereby to set up a circuit for operation of said resistance switching means under the control of said braking coil with full excitation of said field winding.

11. The combination with a traction motor, of an acceleration resistance for said motor, said motor being provided with a field winding, a plurality of normally open electromagnetically operated resistance switches for short-circuiting said resistance in steps, a control relay having a normally closed switch, connections for sequentially closing said resistance switches through said normally closed relay switch, a normally open switch for said control relay, an operating coil for said control relay responsive to the current in said motor during dynamic braking of said motor for opening said normally closed relay switch in response to a predetermined current and closing said normally open relay switch, a normally open switch movable to closed position to shunt said field winding provided with an operating coil controlled by said normally open relay switch, a normally open auxiliary relay switch provided with an operating coil, connections for energizing the operating coil of said auxiliary relay, whereby said auxiliary relay switch is closed to set up a circuit for the operating coil of said field shunting switch

for closure of said field shunting switch when said control relay closes its normally open switch in response to a predetermined dynamic braking current, a braking controller movable from a predetermined position to another position to initiate dynamic braking for said motor, a normally closed first holding switch operated by an intermediate one of said resistance switches connected in circuit with the operating coil of said auxiliary relay, a second holding switch operated by said braking controller connected in parallel with said normally closed first holding switch, said second holding switch being closed when said braking controller is in said predetermined position, but opened to give the control of said auxiliary relay operating coil to said first holding switch when said braking controller is moved to initiate dynamic braking, whereby when said intermediate resistance switch closes, said first holding switch is opened to deenergize said auxiliary relay operating coil thereby to open the operating coil circuit of said field shunting switch and establish full excitation of said field winding, a normally open third holding switch on said auxiliary relay for deenergizing said intermediate resistance switch and all preceding closed resistance switches when said auxiliary relay opens, and a normally closed holding switch on said field shunting switch which is closed when said field shunting switch opens thereby to set up a circuit for reclosure of said short-circuiting switches under the control of said control relay.

12. The combination with a traction motor, of an acceleration resistance for said motor, said motor being provided with a field winding, a plurality of normally open electromagnetically operated resistance switches for short-circuiting said resistance in steps, a control relay having a normally closed switch, connections for sequentially closing said resistance switches through said normally closed relay switch, a normally open switch for said control relay, an operating coil for said control relay responsive to the current in said motor during dynamic braking of said motor for opening said normally closed relay switch in response to a predetermined current and closing said normally open relay switch, a normally open switch movable to closed position to shunt said field winding provided with an operating coil controlled by said normally open relay switch, a manually operated acceleration controller normally in a predetermined position to establish a dynamic braking circuit for said motor including said resistance and movable from said predetermined position to establish a supply circuit for said motor through said resistance, a normally open auxiliary relay switch provided with an operating coil, switching means closed in response to the return of said acceleration controller to said predetermined position for energizing the coil of said auxiliary relay, whereby said auxiliary relay is operated to set up a circuit for the operating coil of said field shunting switch for closure of said field shunting switch when said control relay closes its normally open switch in response to a predetermined dynamic braking current, a braking controller movable from a predetermined position to another position to initiate dynamic braking for said motor, a normally closed first holding switch operated by an intermediate one of said resistance switches connected in circuit with the operating coil of said auxiliary relay, a second holding switch operated by said braking controller connected in parallel with said normally closed first holding

switch, said second holding switch being closed when said braking controller is in said predetermined position, but opened to give the control of said auxiliary relay operating coil to said first holding switch when said braking controller is moved to initiate dynamic braking, whereby when said intermediate resistance switch closes said first holding switch is opened to deenergize said auxiliary relay thereby to open the operating coil circuit of said field shunting switch and establish full excitation of said field shunting switch, a normally open third holding switch on said auxiliary relay for deenergizing said intermediate resistance switch and all preceding closed resistance switches when said auxiliary relay opens, and a normally closed holding switch on said field shunting switch which is closed when said field shunting switch opens thereby to set up a circuit for reclosure of said short-circuiting switches under the control of said control relay.

13. The combination in a propulsion system for a vehicle, of a traction motor, a braking resistance for said motor, an acceleration controller movable from a predetermined position to a running position to establish a supply circuit for said motor, a braking relay for controlling dynamic braking having a coil energized to pick up said relay in response to movement of said acceleration controller to a running position thereby partially to complete dynamic braking connections for said motor, means operated by said coil for establishing a holding circuit for said coil so that said coil remains energized when said acceleration controller is returned to said predetermined position, means operated by said acceleration controller for completing said dynamic braking connections when said acceleration controller is returned to said predetermined position whereby a dynamic braking circuit for said motor is established including said resistance, a braking coil responsive to the current in said braking circuit for controlling said resistance to maintain a predetermined low coasting current in said braking circuit and for deenergizing said braking relay coil, a braking controller movable to decrease the current response of said braking coil thereby to initiate dynamic braking, and a second coil for said braking relay connected to said braking circuit for holding said braking relay picked up until the speed of the vehicle has decreased to a predetermined low value whereupon said braking relay opens.

14. The combination in a propulsion system for a vehicle, of a traction motor, a braking resistance for said motor, an acceleration controller movable from a predetermined position to a running position to establish a supply circuit for said motor, a braking relay for controlling dynamic braking having a coil energized to pick up said relay in response to movement of said acceleration controller to a running position thereby partially to complete dynamic braking connections for said motor, means operated by said coil for establishing a holding circuit for said coil so that said coil remains energized when said acceleration controller is returned to said predetermined position, and means operated by said acceleration controller for completing said dynamic braking connections when said acceleration controller is returned to said predetermined position whereby a dynamic braking circuit for said motor is established including said resistance, switching means for said resistance, a braking coil responsive to the current in said braking circuit for controlling said resistance switching 75

means to maintain a predetermined low coasting current in said braking circuit, a braking controller movable to decrease the current response of said braking operating coil thereby to initiate dynamic braking, means operated by said resistance switching means when said resistance is substantially short-circuited for opening the circuit of said braking relay coil, and a second coil for said braking relay connected to said braking circuit for holding said braking relay picked up until the speed of the vehicle has decreased to a predetermined low value whereupon said braking relay opens.

15. The combination in a propulsion system for a vehicle of a traction motor, a braking resistance for said motor, an acceleration controller movable from a predetermined position to a running position to establish a supply circuit for said motor, a braking relay having a coil energized to pick up said relay in response to movement of said acceleration controller to a running position, means operated by said coil for establishing a holding circuit for said coil so that said coil remains energized when said acceleration controller is returned to said predetermined position, a switch on said braking relay closed by the energization of said braking relay for partially completing connections for dynamic braking, means operated by said acceleration controller for completing said dynamic braking connections when said acceleration controller is returned to its predetermined position whereby a dynamic braking circuit for said motor is established including said resistance, braking control means responsive to the current in said braking circuit for controlling said resistance to maintain a predetermined low coasting current in said braking circuit, a braking controller movable to decrease the current response of said braking control means thereby to initiate dynamic braking, means operated by said braking control means for opening the circuit of said braking relay coil, and a second coil for said braking relay connected to said braking circuit for holding said braking relay picked up until the speed of the vehicle has decreased to a predetermined low value whereupon said braking relay moves to its unattracted position to discontinue dynamic braking.

16. The combination in a propulsion system for a vehicle of a traction motor, an acceleration and braking resistance for said motor, resistance switching means for controlling said resistance to control the acceleration and braking of said motor, a manually operated acceleration controller movable from a predetermined position to a running position to establish a supply circuit for said motor through said resistance for acceleration of said motor, means responsive to the current in the circuit of said motor for controlling said switching means to maintain a predetermined current in said motor during acceleration, a braking relay having a coil energized to pick up said relay in response to movement of said acceleration controller to a running position, means operated by said coil for establishing a holding circuit for said coil so that said coil remains energized when said acceleration controller is returned to said predetermined position, a switch on said braking relay closed by the energization of said braking relay for partially completing connections for dynamic braking, means operated by said acceleration controller for completing said dynamic braking connec-

tions when said acceleration controller is returned to its predetermined position whereby a dynamic braking circuit for said motor is established including said resistance, braking control means responsive to the current in said braking circuit for controlling said resistance switching means to maintain a predetermined low coasting current in said braking circuit, a braking controller movable to decrease the current response of said braking control means thereby to initiate dynamic braking, means operated by at least one of said resistance switching means when said resistance is substantially short-circuited for opening the circuit of said braking relay coil, and a second coil for said braking relay connected to said braking circuit for holding said braking relay picked up until the speed of the vehicle has decreased to a predetermined low value whereupon said braking relay moves to its unattracted position to discontinue dynamic braking.

17. The combination in a propulsion system for a vehicle of a traction motor, an acceleration and braking resistance for said motor, resistance switching means for controlling said resistance to control the acceleration and braking of said motor, a manually operated acceleration controller movable from a predetermined position to a running position to establish a supply circuit for said motor through said resistance for acceleration of said motor, means responsive to the current in the circuit of said motor for controlling said switching means to maintain a predetermined current in said motor during acceleration, a braking relay having a coil energized to pick up said relay in response to movement of said acceleration controller to a running position, means operated by said coil for establishing a holding circuit for said coil so that said coil remains energized when said acceleration controller is returned to said predetermined position, a switch on said braking relay closed by the energization of said braking relay for partially completing connections for dynamic braking, means operated by said acceleration controller for completing said dynamic braking connections when said acceleration controller is returned to its predetermined position whereby a dynamic braking circuit for said motor is established including said resistance, said partially completed connections including an auxiliary relay, shunting switching means for said field winding controlled by said auxiliary relay, braking control means responsive to the current in said braking circuit for controlling said resistance switching means and said field shunting switching means to maintain a predetermined low coasting current in said braking circuit, a braking controller movable to decrease the current response of said braking control means thereby to initiate dynamic braking, means operated by at least one of said resistance switching means when said resistance is substantially excluded for opening the circuit of said braking relay coil, and a second coil for said braking relay connected to said braking circuit for holding said braking relay picked up until the speed of the vehicle has decreased to a predetermined low value whereupon said braking relay moves to its unattracted position to discontinue dynamic braking.

18. The combination in a motor control system, of a resistance for inclusion in the circuit of a motor, an electromagnetically operated

switch for controlling said resistance provided with an armature and an operating coil, a member connected to said armature, a contact arm pivotally mounted on said member at a point intermediate the ends of said arm, a pair of contacts on opposite sides of said arm adjacent the ends of said arm, a spring connected to said arm so as to bias a first end of said arm when said operating coil is deenergized into engagement with a first one of said contacts with the other end of said arm disengaged from the other contact, a normally open relay responsive to the current in the circuit of said motor, an energizing circuit for said operating coil including said arm and said first contact and said relay, whereby when said relay is closed said operating coil is energized to pick up said armature whereupon said arm first pivots on said first contact into engagement with said other contact thereby to close a holding circuit for said coil and then pivots on said other contact against the force applied by said spring to disengage said first contact thereby to open said energizing circuit.

19. The combination, in a propulsion system for a vehicle, of a traction motor, a braking resistance for said motor, an acceleration controller movable from a predetermined position to a running position to establish a supply circuit for said motor, means operated by said acceleration controller for establishing a coasting circuit for said motor including said resistance when said acceleration controller is returned to said predetermined position, an electromagnetically operated switch for controlling said resistance provided with an armature member and an operating coil, a contact arm pivotally mounted on said member at a point intermediate the ends of said arm, a pair of contacts on opposite sides of said arm adjacent the ends of said arm, means for biasing a first end of said arm into engagement with a first one of said contacts with the other end of said arm disengaged from the other contact, a relay responsive to the current in said coasting circuit for closing an energizing circuit for said operating coil to control said resistance whereupon said arm first pivots on said first contact into engagement with said other contact thereby to close a holding circuit for said operating coil and then pivots on said other contact to disengage said first contact thereby to open said energizing circuit, and a braking controller movable to decrease the current response of said relay thereby to initiate dynamic braking.

20. The combination in a propulsion system for a vehicle of a traction motor, an acceleration controller movable from a predetermined position to a running position to establish a supply circuit for said motor, a braking relay for controlling dynamic braking of said motor having a coil energized to pick it up in response to movement of said acceleration controller to said running position thereby partially to complete dynamic braking connections for said motor, means for holding said relay in its energized position when said acceleration controller is returned to said predetermined position, switching means operated by the return of said acceleration controller to said predetermined position for completing said dynamic braking connections, a dynamic braking controller movable from one position to a second position to initiate effective dynamic braking of said motor, and switching means operated by movement of said braking controller to said second position before operation of said acceleration controller to a running

position for energizing said coil to pick up said braking relay and initiate dynamic braking.

21. The combination in a propulsion system for a vehicle of a traction motor, a supply switch for said motor, an acceleration controller movable from a predetermined position to a running position to close said supply switch for operation of said motor, a braking relay for controlling dynamic braking of said motor having a coil energized to a pick it up in response to movement of said acceleration controller to said running position thereby partially to complete dynamic braking connections for said motor, switching means for establishing dynamic braking connections for said motor, means for holding said relay in its energized position when said acceleration controller is returned to said predetermined position to open said supply switch, means operated by the opening of said supply switch for operating said switching means to establish said dynamic braking connections, a dynamic braking controller movable from one position to a second position to initiate effective dynamic braking of said motor, and switching means operated by movement of said braking controller to said second position before operation of said acceleration controller to a running position for energizing said coil to pick up said braking relay and initiate dynamic braking.

22. The combination with a traction motor of a braking resistance for said motor, said motor being provided with a field winding, a plurality of normally open electromagnetically operated resistance switches for short-circuiting sections of said resistance, a control relay having a normally closed switch, connections for sequentially closing said resistance switches through said normally closed switch thereby to short-circuit said resistance, a normally open switch forming a part of said control relay, an operating coil for said control relay responsive to the current in said motor during dynamic braking of said motor so as to open said normally closed switch in response to a predetermined maximum dynamic braking current and at the same time close said normally open switch, and switching means responsive to closure of said normally open switch for disabling at least a part of said field winding.

23. The combination with a traction motor of

- a braking resistance for said motor, said motor being provided with a field winding, a plurality of separately operable normally open electromagnetic resistance switches for short-circuiting said resistance in sections, braking switching means for establishing a braking circuit for said motor including said resistance, a normally closed resistance control switch, connections leading through said resistance control switch for effecting the closing of said resistance switches in sequence, a braking control coil responsive to the current use in said braking circuit for opening said control switch to interrupt the closing of said resistance switches in response to a predetermined braking current, and additional switching means operated by said braking control coil in response to said predetermined braking current for at least partially disabling said field winding.
- 20 24. The combination with a traction motor of a braking resistance for said motor, said motor being provided with a field winding, a plurality of separately operable normally open electromagnetic resistance switches for short-circuiting said resistance in sections, braking switching means for establishing a braking circuit for said motor including said resistance, a normally closed resistance control switch, connections leading through said resistance control switch for effecting the closing of said resistance switches in sequence, a braking control coil responsive to the current in said braking circuit for opening said control switch to interrupt the closing of said resistance switches in response to a predetermined braking current, additional switching means operated by said braking control coil in response to said predetermined braking current for at least partially disabling said field winding, and switching means operated by the closing of an intermediate one of said resistance switches for establishing full excitation of said field winding and for opening said previously closed resistance switches whereupon said braking control coil operates to close said resistance switches with full field excitation.

CERTIFICATE OF CORRECTION.

Patent No. 2,327,809.

August 24, 1943.

CHARLES MacDONALD, ET AL.

It is hereby certified that error appears in the printed specification of the above numbered patent requiring correction as follows: Page 2, second column, line 44, for "controller 27" read --controller 22--; page 5, second column, line 33, for "energiation" read--energization--; line 41, for "R1 to R7" read --R1 to R8--; page 7, first column, line 70, claim 7, after "braking" insert the words --position for decreasing the current response of said braking--; page 9, first column, line 16, claim 12, for "normally" read --normally--; page 11, second column, line 12, claim 23, strike out "use"; and that the said Letters Patent should be read with this correction therein that the same may conform to the record of the case in the Patent Office..

Signed and sealed this 19th day of October, A. D. 1943.

(Seal)

Henry Van Arsdale,
Acting Commissioner of Patents.
